United States Patent Office

Des. 177,459
Patented Apr. 17, 1956

177,459

ELECTRIC HEATER UNIT

Roger L. Crispell, Birmingham, Mich., assignor to General Motors Corporation, Dayton, Ohio, a corporation of Delaware

Application February 10, 1955, Serial No. 34,456

Term of patent 7 years

(Cl. D81—10)

Fig. 1

Fig. 2

Fig. 3

Figure 1 is a perspective view of an electric heater unit embodying my new design placed in vertical position when not in use, showing the bottom, front and one side;

Figure 2 is a perspective view of the unit in horizontal position ready for use, showing the top, front and the same side; and

Figure 3 is a top view of the unit in vertical position as shown in Figure 1.

The dominant features of my design reside in the portions shown in full lines.

I claim:

The ornamental design for an electric heater unit, as shown and described.
